UNITED STATES PATENT OFFICE.

DAVID H. WILSON, OF PHILADELPHIA, PENNSYLVANIA,

PHONOGRAPH-REPRODUCER.

1,390,962.

Specification of Letters Patent. Patented Sept. 13, 1921.

Application filed June 1, 1920. Serial No. 385,800.

To all whom it may concern:

Be it known that I, DAVID H. WILSON, a citizen of the United States of America, residing at 6031 Trinity street, Philadelphia, 5 and State of Pennsylvania, have invented certain new and useful Improvements in Phonograph-Reproducers, of which the following is a specification.

This invention relates to phonographs, and 10 has special reference to reproducers for such instruments.

One important object of the invention is to provide an improved general construction of phonograph reproducers.

15 A second important object of the invention is to provide an improved form of reproducer having an elastically mounted diaphragm.

A third important object of the invention 20 is to provide an improved form of reproducer wherein the diaphragm sound box is supported only at spaced points in an outer shell or holder.

With the above and other objects in view, 25 as will be hereinafter apparent, the invention consists in general of certain novel arrangements of details and combinations of parts hereinafter fully described, illustrated in the accompanying drawings and specifically claimed.

In the accompanying drawings like characters of reference indicate like parts in the several views, and:—

Figure 1 is a transverse section through a 30 reproducer constructed in accordance with this invention.

Fig. 2 is a face view of part of such a reproducer showing the lever support.

Fig. 3 is a side view of the parts shown 40 in Fig. 2.

Fig. 4 is a perspective view thereof.

Fig. 5 is a section of a portion of the reproducer showing the parts disassembled.

Fig. 6 is a detail view of certain supporting rings used herewith.

In the form of the invention herein illustrated, the same being typical of the various forms the invention may assume, there is provided a plate 10 forming the back of the 50 sound box and having its edges threaded. This plate is provided with a centrally disposed nipple 11 which projects rearwardly to fit over the neck 12 of a phonograph horn (the body of the latter not being shown). 55 Screwed onto this plate is a ring 13 which is L-shaped in cross section and forms the side

and front of the sound box, the central part of the latter being left open as shown so as to expose the diaphragm 14, which is peripherally supported in the box by the 60 low elastic rings 15 which are preferably formed of rubber tubing. These parts are so proportioned that, when assembled, the elastic rings are compressed as clearly shown in Fig. 1.

Surrounding this sound box is a casing or housing consisting of a back member 16 having a centrally disposed opening 17 where-through the nipple 11 passes freely so that the two do not contact. Projecting from the 70 front face of this plate adjacent its periphery is an annular flange 18 threaded on its outer surface and fitting neatly around the ring 13 as shown. Screwed on the flange 18 is a ring 19 which is L-shaped in cross section so that 75 the central part of the front of the housing is open.

In order to hold the casing or housing in position and yet have the same sufficiently free from the sound box to prevent transmission of vibrations to the casing and thus interfere with proper tone production certain novel means are employed whereby the two parts are connected, or rather supported relative to each other, at spaced points. These 85 means consist of a pair of annular plates 20 having on each side hardened steel conical projections 21 which are preferably oppositely disposed. The apices of these projections bear respectively on the outside of the 90 sound box and the inner face of the casing which is thus supported from the sound box at space intervals, the supports having acute point contact with the box and casing.

Considering now the needle lever and its arrangement. Projecting from the casing member 19 are spaced posts 22 which are connected at their outer ends by a bridge piece 23 having a centrally disposed threaded aperture 24. Through this aperture passes 100 a thumb screw 25 having a reduced end which engages in an opening in a bowed leaf spring 26 one end of which is fixed to a needle lever 27 while the other end slides freely thereon. On the under side of the 105 lever is secured a cantaliver leaf spring 28 the free end of which lies beneath the spring 26 and rests on the casing member 19.

Secured to the inner end of the lever, which overlies the center of the diaphragm 14, is 110 a screw 29 which passes through the diaphragm 14 and has nuts 30 on each side of

said diaphragm to connect the lever and diaphragm in adjusted relation.

Thus by means of the thumb screw 25 the tension of the spring fulcrum may be varied 5 at will and the action of the needle lever on the diaphragm properly adjusted as desired.

The needle lever is provided in the usual manner, with a needle receiving opening 31 and set screw 32 for holding needles therein.

10 There has thus been provided a simple and efficient device of the kind described and for the purpose specified.

Having thus described the invention, what is claimed as new, is:—

15 1. In a phonograph reproducer, a sound box, a casing surrounding the sound box, and a series of oppositely pointed cones having

their bases fixed substantially in the same plane and their apices engaging the outside of the sound box and the inside of the casing 20 respectively.

2. In a phonograph reproducer, a sound box, a casing surrounding the sound box, the front and back of the casing being spaced respectively from the front and back of the 25 sound box, an annular plate on each side of the sound box, and conical projections extending from the annular plates and engaging respectively with the casing and sound box.

30 In testimony whereof I have affixed my signature.

DAVID H. WILSON.
